ART OF IMAGE FORMATION

Alfred N. Goldsmith and Harry R. Menefee, New York, William Mayer, Larchmont, and Fritz Kastilan, New York, N. Y., assignors to I-R System, Inc., New York, N. Y., a corporation of New York

Application June 19, 1937, Serial No. 149,078

39 Claims. (Cl. 88—16)

Our invention is an improvement in the art of image formation by which sharp images may be produced on suitable media, (such as a photo-chemically sensitized surface, a photo-electrically sensitive apparatus, a ground glass, or the like) by the action of converging light rays which have emanated as diverging rays from objects so positioned relatively to one another and to a lens that that image-forming rays of white light emanating therefrom cannot be converged to a single plane by heretofore known means. Our invention is particularly applicable to motion picture photography and television where lighting conditions are subject to control.

The leading object of our invention is to form on a photo-chemically or photo-electrically sensitive surface images of substantially equal sharpness from objects having a wide range of separation from a lens in the object space thereof. Further objects of our invention are to render identifiable light rays coming from specific regions of the object space by impressing distinctive characteristics on the several groups of rays; and to selectively focus the groups of rays reaching the camera objective and its adjuncts from specific regions in the object space, so as to increase the working range, or, if desired, to produce special effects by shifting the planes of convergence of rays emanating from different regions to image planes offset axially from their natural positions.

The image plane of an objective lens is, strictly speaking, conjugate only to a single object plane. When, however, an objective lens is focused on an object in such object plane, images having circles of confusion of permissible diameter, may be formed of objects at a limited lesser distance from the objective than the strictly conjugate object plane, and of objects at a limited greater distance from the objective than the strictly conjugate object plane. The depth of the region from which images (of point sources) having circles of confusion of permissible diameter may be formed is primarily dependent on the permissible diameter of the circles of confusion in the images of such point source resulting from the use of an objective lens of given focal length and relative aperture. Such diameters should not ordinarily exceed 0.002" (i. e., two-thousandths of an inch) for motion pictures on the film. The depth of such region is referred to herein as the working range of the lens, and every such region may be considered as having a conjugate image plane. Each such conjugate image plane of a different region is positioned a different distance from the second nodal point of the objective.

The total depth of all of the regions containing objects comprised in a scene constitutes, and is herein referred to, as the "object space" of the objective lens, and when such object space exceeds, in depth parallel to the optical axis, the working range of the lens, it has been heretofore impracticable to produce "sharp" images in the same photograph or televised picture of all such objects because actinic rays from all the objects simultaneously activate the entire sensitive surface regardless of the different convergence points of the image rays emanating from the respective objects.

By a "sharp" image of objects in such a region is meant an image wherein

(a) The images of objects in the plane strictly conjugate to the image plane of the objective are as sharply defined as the degree of perfection of the optical corrections of the lens will permit;

(b) The images of objects in the plane strictly conjugate to the image plane of the objective are uniquely produced and free from overlaid and less sharply defined images;

(c) The images of objects lying near or at the inner and outer boundaries of the region are so sharply defined as to have less than the maximum permissible circles of confusion for the image of points in such objects, and

(d) The degree of correction of the optical errors of the objective is high and according to the state of the art, so that image imperfections resulting from chromatic aberration, spherical aberration, astigmatism, coma, zonal errors, or field curvature and the like are inappreciable according to good current practice.

Under the above conditions, we shall speak of a region in the object space as being conjugate to the image plane of sharpest focus of objects within that region, and we shall consider that the image of the said region effectively lies in the said image plane.

By our improvements, actinic rays of substantial activating amount reach the photo-chemically or photo-electric sensitive surface on which an image is to be formed only when the image-forming rays emanating from any object in the object space are converged within circles of confusion of permissible diameter.

It is a primary object of our invention to shift, in a direction approximately parallel to themselves and to the optical axis, one or more groups of image rays converging toward their respective image planes and emanating from a region in the object space as above defined. By such shifts we are enabled to effect convergence to points in the

plane of the sensitized surface of image-forming rays from all the various regions. Conversely, we may shift the plane of the sensitive surface so as to bring it sequentially into coincidence with each of the respective conjugate image planes of the various regions during the convergence of image rays from a given region at such plane and the exclusion of all other activating rays therefrom. Or we may provide a film having multiple parallel sensitive surfaces corresponding to the different regions and on which surfaces rays from the different regions are selectively caused to converge.

A usual objective lens bends image rays emanating from points of an object in its object-space, and relatively close to its anterior principal focal point, to convergence points in a plane, in the lens image-space, lying relatively far from the posterior principal focal point of the lens. Conversely, such lens bends image rays emanating from more distant object points to convergence points in a plane relatively closer to the lens and to its posterior principal focal point.

Converging image rays may be displaced parallel to themselves, and the plane of their convergence points shifted rearwardly without changing their radial relationship to the focal center or to one another, or relative to the radial relationship of the conjugate object points. When a chromatizer is used as hereinafter described, the effect of maintenance of relative radial relationships may be maintained though the radial relationships may be in fact disturbed. Such shifts may be effected by various known optical refracting and reflecting devices, but are most simply effected by interposing in the path of the converging rays an afocal transparent plate. The greater the thickness of the interposed plate, and the higher its refractive index, the further back the plane of the convergence points will be shifted from the lens center or from the former and natural plane of convergence to points of the rays.

By suitably proportioning the thickness of interposed plates, the planes of convergence points of image rays from differently positioned objects in an objective's object-space may be selectively shifted rearwardly different distances and any such plane may be made to lie at the same distance from the center of the lens without changing the size of the image formed by such image points. So long as the thickness of such interposed plate is less than about one-tenth the focal length of the objective, the optical errors introduced thereby will be small in comparison with those of the objective and may be disregarded. Such thickness is amply sufficient to accomplish the desired shifts when using plates of glasses of available refractive index.

Substantially similar shifting of the planes of convergence points of converging image rays may also be effected by devices, such as flat mirrors, or there may be used mirrors or very weak lenses which are so slightly spherical as not to materially affect the radial position of any convergence point relative to the optical axis and are coordinated with very exact timing of the regional illuminations.

Any such device which shifts the convergence points of converging rays rearwardly from the optical center of an objective without changing the image size by materially affecting the radial position of any convergence points relatively to the optical axis of the objective we have desig-

nated generically a differential focuser, or briefly, "difo."

We preferably prevent activation of a sensitive surface by actinic rays which are not converged to points at the plane of such surface by eclipsing or excluding therefrom such non-converged rays. In practice we preferably converge upon a sensitive surface rays emanating from but one region at a time so as to transmit through the objective to the sensitive surface the maximum actinic rays available from each region.

The regional rays of the respective regions are coordinated, by identifying characteristics, with the means for effecting parallel shift of the rays. The identifying characteristics of the rays which we have found most advantageous for the regional distribution and identification thereof are their times of occurrence or periodicity, and their nature or wave-form, including in the latter their color or rate of vibration and their polarity or plane of vibration. The rays, light or illumination defined in the claims as being identifiable or segregatable are characterized by one or more of such attributes, and the claims are to be so understood and interpreted.

The shift parallel to themselves and to the axis of the objective of converging image rays from different regions is preferably effected by their passage through media capable of such displacement in proportion to the distance of the respective regions from the objective, as for instance by the sequential passage of rays from the respective regions through afocal transparent plates of different thicknesses, or indexes of refraction, as, for instance, sheets of optical glass having parallel surfaces.

When characteristics other than periodicity or epoch of the rays are used for identification of a region, a selector, such as a color filter, or polarization filter, is utilized in synchronism with the ray-shifting means to eclipse rays which it is undesirable to have reach the sensitized surface at a particular instant. Such selector, as well as the "difo" coating therewith, may be either movable or stationary.

For most studio work, subdivision of the object space into a foreground region, middle foreground region, middle background region and background region is sufficient for most practical purposes when a lens of reasonable working range is used, but subdivision of the object space into a greater number of shallower regions may be necessary or desirable when a lens of small working range is used. A greater number of subdivisions of the object space may be desirable or necessary when unusually close or unusually distant objects appear in the object space. Subdivision of the object space into a lesser number of regions is permissible when the working range of the lens used is relatively great in proportion to the total object space or when it is unnecessary or undesirable to sharply converge to a point or small circle of confusion image rays emanating from a particular plane or region of the object space. For instance, when all of the principal objects in an object space are in the close foreground and far background, and the middle grounds are relatively empty, the subdivision of the object space into two regions may be entirely adequate. Conversely, when a lens of longer focal length, narrower angle, and short working range is used to depict a scene having a series of important objects at gradually receding positions, it may be necessary to subdivide the object

space into a number of regions substantially equal to the objects to be depicted.

Moreover, where soft or diffused images of objects in a particular region are desired for special effects, the sensitive surface may be deliberately exposed to actinic rays emanating from objects that are so positioned that image rays emanating therefrom are not converged to points or circles of confusion of small diameter at the plane of the sensitive surface, and the "softness" of the image may be accentuated by the use of a plate displacing the convergence points far from the sensitive surface. Other component parts of the picture may thus be brought into sharp contrast with a "soft" part of the picture regardless of the relative positions of the objects with respect to the objective. For instance, images of objects in the foreground and background may both be sharp and the image of objects in the middle ground as "soft" as desired in the same picture taken by a single exposure. In short, our methods permit bringing objects in any or all portions of the object space into focus in the resulting picture, and permits softening or throwing out of focus at will any or all objects in the object space and to any desired extent; both effects being obtainable and controllable within one and the same picture.

In order that light emanating from objects at widely spaced distances from the objective shall form sharp images in substantially the same plane, it is important that—

(a) Light emanating from each region in the object space have an identifying characteristic;

(b) There be passed to the image plane of the objective only such of the rays as emanate from a region conjugate with the image plane or made conjugate therewith by axial displacement of rays from the region to be photographed or televised;

(c) When rays from different regions are permitted to pass through the objective in regular or irregular sequence, and not concurrently, the groups of rays that have emanated from different regions and have been converged be shifted sequentially parallel to themselves and to the optical axis so that their convergence points all lie in a single plane regardless of the regions from which they originated;

(d) When a plurality of regions are concurrently illuminated by groups of rays having different vibration characteristics, the rays undesired at any given instant be eclipsed by a suitable selector to exclude undesired rays from the image plane.

It will thus be seen that for producing uniformly sharp pictures our invention involves means for discriminating between and selectively passing light from different regions to an objective; an objective for converging the rays to convergence points; and means for shifting the convergence points of all the rays to the same plane regardless of the region of origin thereof.

The means for discriminating between and selectively passing the light from different regions to the objective may involve the control of the frequency or time of occurrence or time variation of the intensity of illumination in the several regions when the rate and plane of vibration in the several zones is the same, or may involve the control of the passage sequentially or simultaneously of rays of a particular frequency of vibration or plane of vibration when the rays emanating from the different zones differ in their rates and planes of vibration, or may

involve a combination of the control of any combination of these characteristics.

The control of the frequency of occurrence or of time-variation of intensity of illumination in the different regions may be conveniently effected by the interruption or variation of an electric current, or by occulting mechanism, or by a light beam "sweeping" mechanism, or by any combination thereof which will effect a desired sequential illumination of the several regions.

The control of the rate of vibration or plane of vibration of the rays passing to the sensitized surface may be conveniently effected by color filters, or by "chromatizers" (as later defined), or by polarizers and analysers.

The means for shifting the convergence points of rays passing to the sensitized surface may be afocal plates proportioned to the desired displacement of the convergence points, or reflecting or refracting elements of different optical power, or "chromatizers." Systems effecting discrimination by means of the periodicity of illumination, and effecting the shift of the convergence points by afocal elements, are optically as efficient as ordinary photography during the exposure period for each specific region of the object space and are useable for both black-and-white and color photography, and hence are generally preferable.

All of the systems permit the positioning on the sensitized surface of the convergence points of rays emanating from any region by focusing the objective in the usual way and by shifting the converging rays parallel to themselves and the optical axis and controlling the characteristics of the illumination of the particular region simultaneously. All of the systems permit bringing spotlight-illuminated areas, e. g., the center of interest, into or out of focus at will by control of the character of the spotlight illumination and its relationship to the ray-selecting and ray-shifting means.

Notwithstanding the novel features and results of our systems, the lighting of an object space may be made visually substantially indistinguishable from conventional illumination thereof.

In a preferred exemplification, illumination is furnished by a series of intermittently flashing lamps, such, for instance, as gas or vapor discharge type lamps (e. g., neon-filled or mercury-vapor filled lamps) operating on a suitable voltage, which may be supplied, through a suitable timing mechanism, with brief impulses of unidirectional current or short periods of high-frequency current causing brief and intense flashes from the lamp. The primary source of power may, if desired, be connected directly with the timing mechanism, but it is generally preferable to handle at the timing mechanism only low voltage and amperages and to utilize the timing mechanism for controlling a trigger device, such as a commutator, vacuum tube amplifier, thyratron, or grid glow tube control, through which the lamp operating current is ultimately controlled.

By our improvements we are enabled to form a sharp composite image from image points converged from two or more groups of image rays each of which emanates from an object region spaced differently from the objective than the other object region and each of which groups is appurtenant to and identifiable with a particular object distance or region from the objective.

The coincidence of the points in a single plane is secured by the axial displacement of the plane of convergence points of one or more of the groups, such displacement being along the optical axis and the convergence points of such group retaining substantially the same radial relationship to one another and to the optical axis which the points would have had if undisplaced. By such axial displacement of one ray group, the axial spacing is varied between the normal plane of convergence of its points and the plane of convergence points of another group or groups of image forming rays originating at a distance from the objective different from the displaced group.

This shifting of the rays of one group moves the image points of such group axially relatively to the plane in which rays emanating from another object are converged by the objective, and by admitting to the sensitized surface only rays from regions conjugate with the image plane or made conjugate thereto by axial displacement of rays, and by excluding all other rays, a uniformly sharp image may be produced regardless of the distances of individual objects from the lens.

Briefly summarized, our objects may be attained by systems characterized

(a) By periodic or intermittent regional illumination of the object space and an axial shift of the rays from one or more regions as they are respectively caused to impinge upon the sensitive surface or ground glass, such shift being preferably effected by a rotatable "difo" having one or more afocal plates moved across the optical axis and the image-forming light bundles of rays, or by a stationary difo composed of a plurality of afocal plates of different power to which light from the respective regions is admitted through a shutter synchronized with the illumination periods and with the respective "difo" plates.

(b) By occulting or sweeping beams of light which light up the several regions one after another and by having a movable difo or a stationary difo and movable shutter coordinated therewith so as to effect appropriate displacement of one or more groups of rays, depending on the region illuminated.

(c) By illuminating concurrently different regions of the object space by groups of rays having different planes of vibration, and effecting the axial displacement of the rays of any group necessary to converge its points on the sensitized surface, such displacement being effected by a fixed or movable "difo" having one or more afocal plates, and the rays admitted to any such plate being determined by a fixed or movable selector synchronized with the difo.

(d) By illuminating concurrently different regions of the object space by groups of rays having different rates of vibration and effecting the axial displacement of the rays of any group necessary to converge its points on the sensitized surface. Such displacement may be effected

1. By a fixed or movable "difo" having one or more afocal plates and the rays admitted to any such plate being determined by a fixed or movable selector synchronized with the "difo," or

2. By a fixed "difo" consisting of a "chromatizer" which automatically and simultaneously bends the rays of differently colored light concurrently admitted thereto; the color of the lighting of the several regions being so arranged that the angle of bend of that colored ray by the chromatizer compensates for the difference

in distances of the regions and brings all the rays to convergence points in one plane. In this system, the angular relationships naturally prevailing between converging rays of different colors are varied by the chromatizer so that the effect of maintaining a constant radial relationship between the convergence points is secured notwithstanding the variations effected in the angularity of the rays themselves relative to the optical axis.

The characteristic features and advantages of our improvements will further appear from the following description and the accompanying drawings in illustration thereof.

Fig. 44 is a diagrammatic view illustrating an adaptation of our invention in conjunction with multi-layer film, the distances and parts being

shown out of proportion for the sake of clearness.

For convenience and simplicity we herein illustrate and describe an embodiment of our invention involving the use of a motion picture camera, but it will be understood that the transmitter of television apparatus may be used in lieu of the photo-chemically sensitive surface of the camera.

As illustrated in the drawings, a motion picture camera 1 contains supports for a film having a sensitized surface 2 in the image-space of an objective 3 whose object space comprehends the stage or set 4, which may be deemed to consist of the foreground region 5, the middle foreground region 6, the middle background region 7 and the background region 8. If desired, the rear of the set may consist of a translucent screen 9, on which may be projected from the rear a scene or action complementary to the scene or action in the object space 4.

Systems characterized by periodic regional illumination

As illustrated in Figs. 1 to 6, inclusive, the respective regions of the object space are intermittently illuminated by lamps 10, 11, 12 and 13 which may be flashed on and off in any desired sequence which has been predeterminedly coordinated with the convergence-point-shifter or "diffo," hereinafter described. The flashing lamps may be of known type, as for instance, lamps having gas-filled bulbs through which a high voltage current is discharged controllably at specified times so as to produce a number of flashes per second, each flash being in general of but a few tens of micro-seconds duration but of high lumen output per flash. For instance, we may utilize (illustratively) lamps making 24 flashes of light per second, each flash of approximately ten micro-seconds duration and a luminous output of about 83,000,000 lumens during the flash, equal to about 830 lumen-seconds output per flash. Generally, however, it is preferable to use lamps making 48 flashes per second and have the sensitized surface exposed only during alternate flashes of each lamp.

The light from each lamp is concentrated as much as possible in the region to which the lamp appertains, as for instance, by means of reflectors 14, 15, 16 and 17.

The lights 10, 11, 12 and 13 may be flashed one after another in sequence by connecting them in circuits under the control of contacts as illustrated diagrammatically in Fig. 2.

As graphically illustrated in Fig. 2, a synchronous motor 18 may be connected by the conductors 19 and 19' in circuit with the motor 18a for operating the camera 1. The synchronous motor 18 has connected therewith an insulated shaft 20 having fixed thereto a commutator ring 21 electrically connected with the commutator ring segment 21a; a commutator ring 22 electrically connected with the commutator ring segment 22a; a commutator ring 23 electrically connected with the commutator ring segment 23a and a commutator ring 24 electrically connected with a commutator ring segment 24a. The commutator ring segments 21a, 22a, 23a and 24a make electrical contact in sequence with a brush 25 electrically connected with one polarity of a source 26 of high voltage, high frequency or impulse current. The other polarity of the source 26 is electrically connected with one terminal of each of the lamps 10, 11, 12 and 13. The op-

posite terminals of the lamps 10, 11, 12 and 13 are electrically connected through the brushes 21b, 22b, 23b and 24b with the commutator rings 21, 22, 23, and 24. When the camera is operated by its motor 18a, the motor 18 in synchronism therewith rotates the shaft 20 so as to bring the segments 21a, 22a, 23a and 24a into contact, one after another, with the brush 25 so as to supply current to the lamps 10, 11, 12 and 13 one after another to effect the flashing of these lamps in sequence. An additional portable lamp 10' may have one of its terminals electrically connected with the source 26 and its other terminal connected through a portable conductor 27 with any one of the brushes 21b, 22b, 23b or 24b depending on whether the portable lamp is used for a spotlight in the regions 5, 6, 7 or 8.

Commutator rings and brushes are preferably so operated relatively to the operation of the camera shutter as to complete the circuits effecting the flashing of each of the lamps sequentially during the period that the shutter of the camera is open for the exposure of a single image frame, so that an image of the objects in each of the regions 5, 6, 7 and 8 may be made on the sensitized surface of the film as such objects are illuminated by the respective flashes of the lamps. It may, however, for certain purposes be desirable to imprint the images of the objects illuminated by each flash on a different section or frame of the sensitized film.

It is obvious that the convergence points of the rays emanating from the different regions 5, 6, 7 and 8 during the illumination thereof by the respective flashes would ordinarily lie in different planes after passing through the objective 3, since each region would have its complementary image plane. But by our improvements the convergence points are shifted by displacing the converging rays parallel to themselves and to the optical axis of the objective proportionately to the distances between the image planes naturally conjugate to the respective regions.

This displacement of the convergence points may be effected (Figs. 2 and 3) by means of afocal transparent plates 28, 29, 30 and 31 having thicknesses proportionate to the requisite displacements necessary to bring the convergence points all in the same plane normal to the optical axis regardless of the region from which the rays emanate. These plates are so coordinated with the timing of the lamp circuits that each lamp flashes when its complementary afocal transparent plate is substantially centered in the optical axis of the objective, due leeway in position being allowed in the design.

The positioning of the afocal transparent plates may be conveniently effected by mounting them in a disc 32 which may be the shutter of the camera or may be a separate disc so positioned that the segment thereof containing the afocal plates coincides with the opening of the camera shutter. The shaft 20a carrying the disc 32 is rotated by the motor 18a in synchronous relation with the rotation of the shaft 20 by the motor 18a.

By suitably adjusting the brushes 21b, 22b, 23b and 24b the relative positions of motor shafts may be readily coordinated to produce a flash of the desired lamp when the center of its complementary afocal plate is in the optical axis. Hence the rays emanating from objects in the region illuminated by the flash of the lamp are displaced, after passing through the objective, so that the convergence points of such rays are

shifted from the plane in which they would fall as a result of the action of the objective alone into a plane coincident with the exposed sensitized surface 2 of the film.

It is, of course, quite possible to focus the objective so that the rays from one of the regions will be converged by the objective directly in the sensitized surface plane, but this may necessitate the use of an undesirably thin afocal plate for displacing the converging points from some or all the remaining regions and may also render difficult the dynamic balancing of the disk carrying the afocal plates. Hence, for practical reasons, it is generally desirable to provide afocal plates for each of the regions, and in the absence of the afocal plates none of the rays emanating from objects in the object space are sharply converged on the sensitized surface plane.

While, for simplicity of illustration, we have shown a single lamp illuminating each region, it will be understood that there will be concentrated on each region the rays from as many lamps as are necessary to give the desired intensity of lighting to that particular region, and that the lamps of a particular region may be flashed simultaneously, or may be flashed sequentially during the period when the afocal plate complementary to that particular region lies in the optical axis. Such sequential flashing of a number of lamps in a region while its complementary afocal plate is in the optical axis merely involves a multiplication of timing contact devices so as to provide an individual control for each lamp in properly timed relation to the movement of the afocal plate or any equivalent electro-mechanical timing device.

Where the spotlight 10' is to be maintained upon a person or center of interest moving through the different regions of the object space, one terminal of such spotlight may be permanently connected to the source of current and the other terminal of the spotlight brought into contact, manually or mechanically, with the respective brushes, complementary to the region in which the center of interest is at the moment, so that the spotlight will be flashed in synchronism with the afocal plate appropriate to the region occupied. The flashing spotlight 10' may be conveniently mounted upon a usual but heavier form of swivel microphone boom 33. One of the terminals of such spotlight is connected permanently with the source of current and the other terminal of such spotlight may be connected through a conductor 34 with a contact 35 near the swivel bearing and which makes lighting contact, as the boom is moved, with the contact plates 36, 37, 38 and 39 connected with the respective brushes 21b, 22b, 23b and 24b. As the boom carries the spotlight from one region to another, the source of current for flashing the light is shifted from one brush to another, so that correct synchronization between the flashes and the afocal plates is constantly maintained. If the spotlight is kept in one position but tilted and rotated to follow the center of interest, the correct synchronization between the flashes and the afocal plates can similarly be maintained either manually or by a suitable contactor assembly.

Instead of controlling the flash of the lamps in synchronism with the complementary plates of a dicro by a separate timing device synchronously driven in appropriate timed relation- 75 ship to the camera shutter and dicro, as above

described, the timer may be mounted as an integral part of the camera structure, and the film feeding mechanism, the diaphragm mechanism and the flash controlling mechanism driven by the same motor, as illustrated in Figs. 4, 5 and 6.

As shown in these figures, a motion picture camera 1 has an objective 3 mounted in a usual form of turret by which any one of a series of objectives 3 may be brought into alignment with the aperture 1a (Fig. 6). A usual camera drive shaft 1b has fixed thereto, in lieu of the usual shutter for controlling the aperture 1a, the diaphragm disk 32' containing the afocal plates 28', 29', 30' and 31' which are moved sequentially past the aperture 1a behind the objective 3.

The shaft 1b acts through suitable gearing upon the film sprocket 40 to feed the film 41 step by step past the film gate 42 so that the film is stationary during the passage of the plates 28', 29', 30' and 31' past the aperture 1a.

A bracket 43 is fixed to the camera casing and supports an electric motor 44 and a flash timer 45 having a shaft 46 coupled to the motor shaft and to the camera shaft 1b.

The shaft 46 has mounted thereon a series of insulated cams 47 (Fig. 5), each of which is adapted to engage and rock one of a series of contact vibrators 48 mounted on insulating shoes 49 which are adjustable around yokes 50 to vary the time of occurrence of contact between the cams 47 and the contact vibrators complementary thereto. A source of low voltage current, such as a battery 51, (Fig. 4) has one of its poles connected by suitable conductors with terminals 48a, 48b, 48c and 48d of the respective vibrators 48. The complementary terminals 48a', 48b', 48c' and 48d' are respectively connected with low tension windings of ignition coils 52a, 52b, 52c and 52d, which also have connected therewith spark gap condensers connected with the battery 51. The high tension windings of the ignition coils 52a, 52b, 52c and 52d are connected through suitable conductors with the vapor lamps 10, 11, 12 and 13, which have suitable condensers and bleeder resistances 53 in parallel and grounded surge resistances 54 connected therewith.

The foregoing timing mechanism closes tickler circuits of the lamps 10, 11, 12 and 13 so as to cause flashing of the lamps by current supplied from a high voltage source, such as a central station, from which alternating current flows through the conductors 55 and 56 through the plate transformers 57 and filament transformers 58 of suitably grounded rectifier tubes to provide the high voltage DC current through the conductors 59a, 59b, 59c and 59d to charge the condensers which operate the vapor lamps efficiently in flashes.

The number of vibrator contacts and circuits controlled thereby will of course be varied to conform with the number of the regions into which the object space of the objective 3 is to be divided, and the blocks 49 will be so adjusted angularly that the flash of each lamp will occur during the transit of the complementary afocal plate across the optical axis. A group of rays emanating from each region will therefore pass in sequence through, and be converged by, the objective 3, and the planes of the convergence points of the respective groups of rays will be shifted axially along the optical axis so as to bring them into coincidence with the sensitized surface 2 of the film 41. Since no region has a depth greater than that which the

objective 3 is capable of photographing without the formation of circles of confusion of objectionable size, the composite picture formed by the rays emanating in sequence from the several regions will be formed entirely by the action of rays converged to points or at least converged within the circles of confusion of unobjectionable size.

The difference in the relative sizes of the circles of confusion in images of object points in the object space when the rays from all such objects are simultaneously converged by an objective and the relative sizes of the circles of confusion, where the images of the object points in the object space are made in accordance with our invention, is diagrammatically and graphically illustrated in Figs. 1A and 1B.

If it be assumed that the objective 3, at a certain working speed or relative aperture, be focused in Fig. 1 so that the sensitized surface of the film is in a plane conjugate to a plane 60 in the foreground region 5, and that the object space is constantly and uniformly illuminated, then the graph 61, (the curved shape of which resembles a skewed parabola) indicates the increasing size of the circles of confusion formed by rays emanating from objects in front of or behind the plane 60. The objects in the plane 60 will form circles of confusion of minimum diameter, corresponding, presumably, to a sharply defined image, and which minimum diameter may be deemed to correspond to the distance between the nadir 62 and the point 63. As the distance of the object from the plane 60 increases or diminishes, the diameters of the corresponding circles of confusion increase toward an arbitrarily selected maximum, which should preferably not exceed .002 inch for images on motion picture film, and which may be indicated by the distances 62—64. The distance between the upper ends 65 and 66 of the legs of the parabolic-shaped graph at the height of the point 64 is indicative of the region or working range of the lens 3 within which objects will generate images containing circles of confusion within the permissible limit.

Objects beyond the working range of the lens will be too "soft," or out of focus, to be tolerable.

If the objective be focused on objects in the plane 70 in the middle foreground region 6, then the distance between the upper ends 71 and 72 of the parabolic graph 73 will be indicative of the region or working range of the lens when so focused and within which working range objects will generate images containing circles of confusion within the permissible limit. In this case the objects that are in exact focus will form images having circles of confusion of minimum diameter slightly smaller than is the case with objects in the plane 60 when the objective is focused on the plane 60.

If the objective be focused on objects in the plane 80 in the middle background 7, the distance between the upper ends 81 and 82 of the parabolic graph 83 will be indicative of the region or working range of the lens when so focused, and within such range objects will generate images containing circles of confusion within the permissible limit and the smallest circles of confusion generated will be smaller than any circles of confusion generated when the lens is focused on either the plane 60 or the plane 70.

If the objective 3 be focused on the plane 90 in the background, the distance between the forward upper end 91 of the parabolic graph 90 and the projection of this graph beyond the

background itself is indicative of the region or working range of the lens when so focused. Objects within such working range will generate images containing circles of confusion within the permissible limit and the smallest circles of confusion will be smaller than the minimum size of any circles of confusion generated by the objective when focused on the planes 60, 70 or 80. It will, of course, be understood that if the background did not obstruct the object space, images would also be formed with permissible circles of confusion from objects between the background and the far end of the parabolic curve 92.

It will be noted from the parabolic curves that the objective 3 has a lesser working range in front of a plane of sharpest focus than behind a plane of sharpest focus for each setting of the lens, and that the curves become of sharper minima, and hence indicative of less working range of the lens, as the plane of focus approaches the lens, and that the minimum realizable circle of confusion and the greatest working range is obtained by sharp focusing on a plane toward the background. But regardless of the plane on which the objective is focused, it is impossible to secure an image having permissible circles of confusion of objects spaced over the entire object space in the case illustrated. Hence it is impossible in this case, with any one setting of the objective alone, to obtain desired results of forming images with satisfactory sharpness (reduced diameter of circles of confusion in the image) over the entire set from foreground to background.

In Fig. 1B we have indicated graphically the effect of our improvements upon the working range of the lens and the diameter of the circles of confusion formed on the sensitized surface from rays emanating from anywhere within the object space. In this figure the full line curve 100 indicates the approximate performance of our improved system when the illumination of the regions by the flashing lamps and the displacement of the convergence points of the image rays by the afocal plates are properly coordinated. The maximum permissible diameters of the circles of confusion are indicated by the position of the line 101. The objective 3 will be focused so that rays emanating from objects in the plane 60 will be converged at points in a plane in front of the sensitized film surface a distance equal to the displacement power of the thinnest afocal transparent plate 28. With the lens so focused and the foreground illuminated, the convergence points of rays emanating from objects in the foreground region 5 will be displaced rearwardly so that they fall on the sensitized surface or sufficiently close thereto to form circles of confusion of lesser diameter than the maximum permissible. The next thicker afocal transparent plate 29 has a displacement power equal to the distance between the plane of the sensitized film surface and the plane in which the objective 3 (without further adjustment) converges to points, rays emanating from objects in the middle foreground region 6. Hence when the middle foreground 6 is illuminated and the afocal transparent plate 29 interposed in the path of the converging rays, the convergence points of such rays will be shifted rearwardly into coincidence with the plane of the sensitized surface, or so close thereto that the circles of confusion formed will be of less diameter than the maximum permissible. The next thicker afocal transparent plate 30 has a displacement power equal to the

distance between the sensitized film surface and the plane in which rays emanating from the middle background region 7 are normally converged by the objective 3 without further adjustment.

5 Hence when the middle background region 7 is illuminated and the afocal transparent plate 30 is interposed in the optical path, the convergence points of rays emanating from the region 7 will be shifted backward into coincidence with the plane of the sensitized film surface or so close thereto that the circles of confusion formed thereby will be of less diameter than the permissible maximum.

15 The next thickest afocal transparent plate 31 has a displacement power equal to the distance between the sensitized film surface and the plane in which the objective 3 without further adjustment normally converges to points the rays emanating from objects in the background region 8. Hence when the background region 8 is illuminated and the afocal transparent plate 31 is positioned in the optical axis, the plane in which the rays emanating from the region 8 are converged to points by the objective 3 is shifted 20 rearwardly into coincidence with the sensitized film surface or so close thereto that the circles of confusion formed thereby are of less diameter than the permissible maximum.

25 Since the flash of the front lamp 10 illuminates only the foreground region 5 to an intensity sufficient to photographically activate the particular sensitive film employed, all or substantially all of the rays passing through the objective 3 and plate 28 will be converged sufficiently close to the sensitized surface that the diameters of the circles of confusion will all be less than the permissible maximum and will vary only in proportion to the spacing of objects within the normal working range of the objective 3, as illustrated by the first loop of the graph 100.

30 The flash of the lamp 11 will illuminate only the region 6 to an intensity sufficient to photographically activate the particular sensitive film employed, the rays therefrom passing through the objective 3 and the plate 29 will likewise be converged to points in a plane substantially coincident with the plane of the sensitive film surface, or so close thereto that the diameters of the circles of confusion will vary only in proportion to 35 the spacing of objects within the normal working range of the objective 3 at the distance of the region 6, as illustrated by the second loop of the graph 100.

35 The flash of the lamp 12 illuminates only the region 7 to an intensity sufficient to photographically activate the sensitive film surface and hence rays passing through the objective 3 and plate 30 are converged to points in a plane substantially coincident with the sensitive film surface 40 and the diameters of the circles of confusion vary only in proportion to the spacing between objects within the normal working range of the objective 3 at the distance of the region 7, as illustrated by the third loop of the graph 100.

45 The flash of the lamp 13 illuminates only the background region 8 to an intensity sufficient to photographically activate the particular sensitive film employed. Hence rays passing through the objective 3 and the plate 31 are converged to points in a plane substantially coincident with the sensitive film surface, and the diameters of the circles of confusion formed thereby vary only in proportion to the spacing of objects within 50 the normal working range of the objective 3 at

the distance of the region 8, as illustrated by the fourth loop of the graph 100.

It will be noticed that the upper points of inflection of the graph 100 have been shown slightly above the crossing points of the dotted line curves 81, 73, 83 and 82 illustrating the respective working ranges of the objective 3 alone at the various regional distances. This is so shown because there may be a certain amount of spillover of light between the adjacent regions, but such spillover may be so limited as to keep the apices of the graph 100, at all studio distances from the lens, below the maximum circle of confusion limit indicated by the line 101.

It will thus be seen that by our invention there is provided an optical system of universal working range for the object space or within the region of suitably controlled illumination and that an image of each object is imprinted on the sensitized surface by rays that converge to points substantially in the plane of such sensitized surface regardless of the positions of the objects themselves.

If, for instance, as shown in Fig. 7, the object space contains the objects 108, 109, 110 and 111 in the respective regions 5, 6, 7 and 8, the flash of the lamp 10 will imprint on the sensitive surface a sharp image of the object 108 as shown in Fig. 8, leaving the remainder of the sensitive surface unactivated; the flash of the lamp 11 will imprint on the sensitized surface an image of the unobscured portion of the object 109, as shown in Fig. 9, without further activating the area containing the image of the object 108 and without activating the remainder of the sensitive surface; the flash of the lamp 12 will imprint on the sensitive surface an image of the unobstructed portion of the object 110, as shown in Fig. 10, without further activating the areas occupied by the images of the objects 108, 109, and without activating the remainder of the sensitive surface; and the flash of the lamp 13 will imprint on the sensitive surface an image shown in Fig. 11 of the unobscured portion of the object 111 without further activating the areas occupied by the images of the objects 108, 109 and 110. Hence the developed film will show, as illustrated in Fig. 12, a composite image of all of the objects, and each portion of the composite image will be sharp.

Periodical regional illumination by occulted rays

In lieu of or to supplement the periodic regional illumination by flashes of intermittent light, we may periodically illuminate the regions 5, 6, 7 and 8 in timed relation to the convergence points displaced or "dalloo" by means of a source of constant illumination whose rays sweep as a narrow beam in a regular or irregular sequential order conforming to the order of the "dalloo" elements.

For instance, as shown in Fig. 13, we may provide adjacent to the front of the object space a set of powerful illuminants 10a, 11a, 12a and 13a. Each illuminant is preferably of considerable length physically or in its optical equivalent of light distribution by reflectors, distributing lenses or other suitable optical means, and may be equal in illuminating effect to lights extending the full width and height of the set or object space.

Each illuminant may consist of a high efficiency incandescent lamp of the linear filament type, as illustrated in Figs. 14 and 15, and each lamp may have its terminals connected in a cir-

cuit which supplies current thereto continuously so that the light is constant. In the embodiment illustrated, each of the lamps 10a, 11a, 12a and 13a is mounted in a frame or bracket 111, and the framework has fixed bearings 112 and 113 on which antifrictionally supported bearings 114 and 115 rotate. A parabolic, elliptic, or cylindrical reflector 116 is mounted on the bearings 114, 115 with the filament of the lamp in approximately the focal line of the reflector.

An opaque housing 117 is also mounted on the bearings 114, 115, and supports a semi-cylindrical condenser lens 118 which concentrates the total emitted light into a narrow beam or sheet of the desired dimensions. The frame 111 may be provided with adjustably hinged shutters 119, by the adjustment of which the shutter opening and the limits of position of the emitted light sheet can be further regulated.

The rotary bearings 114 are toothed for engagement with pinions 120 driven in timed relation with the movements of the afocal plates 28, 29, 30 and 31, as, for instance, by synchronous motors 121 fed from the same alternating current sources as the synchronous motor 18a for actuating the driving mechanism of the diffo plate and camera.

It will be understood that, as the casing 117 and parts connected therewith are rotated with the shutters 119 retracted to provide an adequate opening, the sheets of light emanating from the lenses 118 sweep over the set so as to illuminate the regions 5, 6, 7 and 8 one after another as the afocal plates 28, 29, 30 and 31 move across the optical axis of the objective. Hence the objects in the respective regions are illuminated to photographic intensity coincidentally with the positioning of the respective afocal plates to displace the planes of the convergence points normally conjugate with such regions to the plane of the sensitized film surface.

Instead of sweeping sheets of light the depth of the set, as above described, a series of lamps 10a', 11a', 12a' and 13a', similar to the lamps 10a, 11a, 12a and 13a, may be respectively positioned adjacent to the regions 5, 6, 7 and 8, as shown in Fig. 16. The shutters 119 of these lamps are partially closed to form a comparatively narrow slit, so that the flat beam from each lamp 10a', 11a', 12a' and 13a' will illuminate only the zone to which such lamp is appurtenant. In such set up, the housings 117 and the lenses 118 will be initially so adjusted angularly relative to one another that the rotation of the lenses 118 will cause the illumination of the region by one lamp to be discontinued as or before the illumination of the next region by its lamp commences.

If desired, supplementary lamps 10'', provided with the shielding and operating mechanisms above described, may be disposed in any region and the effulgence of light therefrom so timed as to synchronize with the position of the afocal plate which is complementary to the region illuminated by such lamp or lamps 10''.

In some cases the light from a single lamp may suffice when the light therefrom is swept over the set in the manner described in connection with Figs. 13, 14 and 15, or, as shown in Fig. 17, the light from a single reversed lamp 10a may be swept across the set so as to illuminate the several regions to photographic intensity, one at a time, by means of a reflector, such, for instance, as a rotating polygonal reflector 123 driven through suitable gearing by a synchronous motor 124 in timed relation to the movement of the

afocal plates of the "difo" by the synchronous motor 18a.

In the foregoing instances, we have assumed progression of the illumination from front to rear in order to simplify the illustration and description of illustrative types of optical systems of the increased working range utilizing progressive periodic illumination of regions in the object space to permit the identification at the objective 3 of light coming from each region, and description of the complementary differential displacement of convergence point planes. It should, however, be understood that any desired sequence of lighting of the regions of the object space falls within the scope of our invention, and the differential displacement of the planes of the ray convergence points will generally be correspondingly modified so that all of the ray convergence points are brought to substantially the same image plane.

In some cases where intermittent illumination of the different regions is used as the method of ray-group identification, it is desirable to reduce spill-over effects due to illumination from one region partially entering another region adjacent thereto by changing the sequence so that certain adjacent regions are not consecutively illuminated. For instance, the sequence of illumination may be foreground, middle background, middle foreground and background; or foreground, background, middle foreground and middle background. By increasing the number of regions to five or more and increasing the number of complementary difo elements correspondingly, the sequence may be made such that no two adjacent regions are consecutively lighted. For instance, the sequence may be foreground, middle ground, background, middle foreground, middle background, and repeat.

It should further be understood that while we prefer the use of a difo comprised of afocal plate elements for effecting progressive coincidence of convergence-point-planes, conjugate to the respective regions, with the sensitized surface, such coincidence may be secured by the movement of a lens element to vary the focal length of the lens, or by means for shifting the sensitized surface toward and from the lens, or by means for reflecting the converging rays so as to vary the length of the paths thereof, but all such motion or displacement of beams must be synchronized with the regional illumination so as to exclude from the sensitized surface any effective actinic rays emanating from objects whose image rays do not converge at the sensitized surface in circles of confusion within the permissible maximum diameter, and furthermore such means should effect the displacement of the convergence points of rays from the different regions along the optical axis without materially changing the positions of the convergence-points radially to the optical axis.

The periodic photographic illumination, to which we have hereinbefore referred, and which must, of course, occur while the camera shutter is open, should not be confused with mere non-photographic visual illumination which may be provided concurrently with or alternately to the photographic illumination to eliminate or minimize the tiring of the eyes by possible flicker. For instance, there may be used sensitized surfaces which are photosensitive to rays beyond the visible spectrum. The photo-illumination, by invisible rays, of one region after another, may be effected concurrently with the visual illumina-

tion of the entire object space by rays within the visible spectrum, which are excluded from the sensitized surface by means of suitable filters. Or the object space as a whole may be continuously illuminated by rays within the visible spectrum to an extent which is too weak or of such color that it does not materially activate the sensitized surface during the brief exposure thereof necessary for the making of an image of the particular objects within the zone of intense photographic illumination. Or the set may be illuminated by the same or complementary flashing or occulting lamps during the period when the shutter is closed, as well as during the period when the shutter is open, and the periods of darkness unilluminated by flashes are rendered so brief as to be visually imperceptible. In such cases the flashes during the closed shutter period preferably occur at the beginning of this period and are of gradually decreasing amplitude. Or the light flashes when the shutter is open may be so timed as to occur immediately upon the opening of the shutter and immediately before it is closed, with a time interval between flashes corresponding roughly to the time interval when the shutter is closed. Numerous arrangements of timed illumination within the photographing period, and outside that period respectively, may be selected and fall within the spirit of our invention.

Modified forms of "difo"

When sweeping or scanning beams moving over or from the set are employed, so that there is no abrupt change of photographic illumination from one region to another, it may be desirable to correspondingly modify the difo action. As illustrated in Figs. 18, 19 and 20, this may be effected by forming the difo elements of complementary transparent plates 28a, 28b, 29a, 29b, 30a, 30b, 31a, 31b. The plate may be of wedge shape cross-section throughout or may have flat plane parallel thickest portions of widths equal to the beam width and taper therefrom to zero thicknesses. The plates of each complementary pair are mounted in registration with apertures in oppositely turning rotors 32a, 32b. The opposed and oppositely moving transparent wedge sections of such plates are (to a close degree of approximation for slightly separated wedges) the optical equivalent of a transparent afocal plate of continuously varying thickness between zero and twice the thickness of either wedge.

The rotors 32a and 32b are rotated by synchronous motors (not shown) in synchronous relation to the flash controlling motor 18 and the camera motor 18a of Figs. 1 and 2 and are so timed that the thin portions of a pair of wedges overlap when image rays from objects at a short distance are passing therethrough and the gradually increasing thicker portions gradually overlap as image rays from gradually increasing object distances pass therethrough to the objective. At any instant the combined wedge thickness has a displacement power, upon the convergence points of image rays passing therethrough from the several regions 5, 6, 7 and 8, commensurate with the displacement required to bring such points into coincidence with the sensitized surface.

Stationary difo elements

As illustrated in Figs. 21 to 23, the difo elements of varying thickness may be arranged as a series of sets of alternating segments in a disk 32c and the passage of light therethrough con-

trolled by a complementary sequentially apertured shutter $32c'$. For instance, four segmental diffo plates $28c$, four segmental diffo plates $29c$, four segmental diffo plates $30c$, and four segmental diffo plates $31c$, all of similar size and shape, are arranged in alternation with their apices at a common center in the optical axis of the objective 3 . The shutter disk $32c'$ preferably contains four equi-distant segmental openings $32c''$ and is mounted in a rotor $32d$ with its center in the optical axis of the objective 3 . The rotor is provided with bearing surfaces $32e$ which rotate in the circular seat $32f$. The periphery of the rotor is provided with teeth which mesh with a pinion $32g$ which may be driven by a motor in synchronism with the motors 18 and $18a$ and in timed relation with the periodicity of the regional illumination. The shutter apertures are coordinated so that they will register with the diffo plates $28c$ to permit the passage of rays emanating from the foreground region 5 when it is illuminated; so that such apertures will register with the diffo plates $29c$ to permit the passage of rays emanating from the region 6 when such region is photographically illuminated; so that such apertures will register with the diffo plates $30c$ to permit the passage of rays emanating from the region 7 when such region is photographically illuminated; and so that the shutter apertures will register with the diffo plates $31c$ to permit the passage of rays emanating from the region 8 when such region is photographically illuminated.

Use of diffo with unidentifiable illumination

While diffos composed of afocal elements of different thicknesses are primarily designed for use in conjunction with identifiable illumination to differentially shift the convergence point planes of several groups of rays from different regions, such diffos are capable of use independently of ray-group identification to provide for the statistical averaging of a multiplicity of images of objects concurrently illuminated by rays lighting the entire object space of an objective without the light rays being identifiable as groups attributable to different regions. Pictures thus obtained are not really sharp anywhere. That is, the entire picture is rather "soft" but such general softness eliminates any basis of comparison between "in focus" and "out of focus" portions and this use of the diffo to promote an average of general softness makes possible certain desired effects.

For such use of the diffo, as well as for use thereof in conjunction with identifiable groups of light rays, we may so construct the diffo as to permit of the passage of different amounts of light through the different afocal plates therein of varying thickness, as illustrated, for example, in Figs. 24 and 25.

As illustrated in Fig. 24, and diffo disk $32h$ has set therein the diffo plates $28h$, $29h$ and $30h$ of increasing thicknesses so as to offset the convergence point planes of converging image rays passing through the respective afocal plates. The plates $28h$, $29h$ and $30h$ are made of progressively greater angular width so that the afocal plate $29h$ takes a shorter time passing a camera opening $1a$ than does the plate $28h$, and the plate $30h$ takes a shorter time passing the camera opening $1a$ than does the plate $29h$. When the diffo is used independently of identifiable ray-groups, three afocal plates will ordinarily suffice, but when the diffo of this type is 75

used with identifiable ray-groups emanating from different regions, the number of afocal plates will, of course, be made to correspond to the number of regions.

5 Where the background objects are of less importance than the middle and foreground objects and it is desired to preserve greater sharpness in images of the foreground than that of the middle ground and background, the diffo will be rotated 10 in the direction of the arrow so that the time during which the film will be exposed to a picture in which the foreground is to be in sharp focus will be greater than the time for the middle ground, which in turn will be greater than the time for the background. If the background objects are of greater importance, the widths of the successive sectors should be increased sequentially instead of diminished.

Fig. 25 illustrates a further form of diffo which 20 accomplishes substantially the same result as the diffo shown in Fig. 24 and is suitable for use in either our increased range system or for use without identifiable ray-groups. As illustrated in Fig. 25, the sectors $28i$, $29i$ and $30i$ (which correspond respectively to the foreground, middle ground and background) are of substantially equal angular width and of increasing thicknesses. They differ, however, among themselves in light transmissibility. For instance, the foreground sector $28i$ may be quite transparent; the middle ground sector may be slightly absorbent of light (due to making it of grey glass or to putting a neutral density plate in front of it); and the background sector may be similarly made 30 still more absorbent of light. In this manner the light reaching the film will be caused to progressively decrease as the convergence point planes are shifted farther and farther back due to the sequential passage of the afocal plates $28i$, $29i$ and $30i$ past the opening $1a$. If, however, it is desired to transmit the least light when the convergence point plane is least shifted, the afocal plate $28i$ will be made most absorptive and the plates $29i$ and $30i$ will be made progressively less 40 absorptive of light.

Our diffo may also be used in conjunction with an objective of variable focal length focused on an object space illuminated uniformly so that the ray-groups emanating from different regions are not identifiable. By suitable coordination of the lens adjustment and the diffo, it is possible to produce sequential photographs one of which has a sharp foreground and soft background, and the other of which has a soft foreground and sharp background, the images of the same object being of substantially the same size in both pictures. For such uses but two afocal plates at the most are required.

Differential regional illumination by rays having different planes of vibration—Rotating diffo and analyzer

To carry out our method of photography by photographically illuminating the different regions of an object space by rays having different planes of vibration, we may utilize the apparatus illustrated diagrammatically in Figs. 26 to 29.

For such purpose the respective regions 5 , 6 , 7 and 8 may be continuously illuminated by suitable sources of light, such as lamps $10a'$, $11a'$, $12a'$ and $13a'$ with their housings stationary and so positioned angularly that the light from each lamp is thrown upon the region to which it appertains. In addition to, or in lieu of the condensing lens, the shields 116 support light polarizers $10j$,

11j, 12j and 13j, such as the material polaroid, by which the planes of polarization of the light emitted by the lamps through the polarizing plates may be controlled so that the light vibrates in different planes in the different regions 5, 6, 7 and 8. For instance, the polarizer 10j may polarize the light emitted from the lamp 10a' to a vertical plane as viewed from the objective 3; the polarizer 11j may polarize the light emitted from the lamp 11a' to a plane inclined 30° to the vertical; the polarizer 12j may polarize the light emitted from the lamp 12a' to a plane inclined 60° to the vertical; and the polarizer 13j may polarize the light emitted from the lamp 13a' to a horizontal plane. All of the foregoing planes are considered as being viewed from the objective 3 along the incident light rays (Fig. 26). Depending on the nature of the surfaces of the objects in the object space and the angle of incidence of light thereon, the plane of polarization of the thereon incident light will be maintained by the reflected light emanating from such objects.

With such a system of illumination there may be mounted on the camera shaft 1b between the film and the objective 3 a diffo disk 32j having set therein four transparent afocal plates of different thickness and segmental shape. There are also mounted on the shaft 1b a series of similar disks 140, each containing a set of similar polarizing analyzers 140a, 140b, 140c and 140d complementary to the respective afocal plates of the diffo 32j. The analyzers 140a are such that they primarily and predominantly permit the passage of light having a vertical plane of vibration emanating from the region 5, and the convergence points of such rays are displaced by the first afocal plate of the diffo 32j into coincidence with the sensitized surface 2. The analyzers 140b pass primarily light having a plane of polarity 30° from the vertical emanating from region 6. When the analyzers 140b are moved into the optical axis they primarily pass light emanating from region 6 and the convergence points of such rays are shifted by the second afocal plate of the diffo 32j a distance sufficient to bring them into coincidence with the sensitized surface 2. The analyzers 140c primarily pass light having a plane of vibration 60° from the vertical, and when these analyzers are in the optical axis there pass therethrough only rays emanating from the region 7, and the convergence points of such rays are shifted by the third afocal plate of the diffo 32j into coincidence with the sensitized surface 2. The analyzers 140d primarily pass rays having a horizontal plane of vibration, and when such analyzers are in the optical axis they primarily pass the rays emanating from the region 8 and the convergence points of such rays are shifted by the fourth afocal plate of the diffo 32j into coincidence with the sensitized surface 2.

The analyzers are preferably placed close in front of the objective to reduce glare from undesired light and depolarization by reflection. The multiplicity of identical analyzers placed one behind the other is preferably used to increase the discrimination of the analyzers against light from undesired regions; that is, to more effectively exclude light which does not have the selected plane of polarization. In the event polarization of the media is imperfect at the ends of the visible spectrum, the selectivity may be increased by photographing through a filter absorbing the ends of the spectrum to an appropriate extent, e. g. a greenish-yellow filter, or by placing similar

filters in front of the lights illuminating the regions.

We have found that in some cases the analyzers may all be cut from a single piece of polarizing material without patching.

If it is desired to supplement the general illumination of the object space of Fig. 26 by special illumination of a center of interest, a spotlight similar to 10' may be provided with a rotatable polarizer having segments which may be so positioned that the plane of polarization of the emitted light corresponds to the illumination of that region in which the center of interest is momentarily located. As the center of interest moves from region to region the polarizer is rotated manually or automatically to bring into action a polarizing segment which polarizes the emitted light to correspond with the polarity of light in the region occupied by the center of interest.

While our improvements are primarily designed for studio work, it is possible to throw light polarized at right angles to the sky-light on a nearby center-of-interest out of doors and to admit or exclude such booster light by means of our diffo plates to achieve novel and useful effects in increasing the optical working range of the photographic system.

The use of polarized light as a means of effecting identification is particularly desirable when background projection on the screen at the rear of the object space is utilized. Such rear projection may be through a screen of polarizing material, such as polaroid. In such case the light passing through will be polarized in a plane determined by the orientation of the polaroid screen. If the back of the screen is coated with a diffusing material, as is necessary for translucent projection, it is possible nevertheless to polarize the light thereafter passing through the screen and thus to supply properly polarized light for effecting the differential desired. Should a mirror-like or specular screen be used at the rear of the set and a scene be projected thereon from the front, the reflected light may retain its polarity if the necessary optical conditions are met. The plane of polarization may be maintained throughout a wide range of positions for the camera by using suitably constructed reflective screens, such as described in the "Funkt-technische Monatshafte" for July, 1936, Supplement, pages 53 and 54.

Non-rotating diffo and analyzer

In lieu of using a rotating diffo and set of rotating analyzers to photograph an object space having regions respectively illuminated, as shown in Fig. 26, by a polarized light of different polarity, we may use a stationary diffo and a group of stationary segmental analyzers in close juxtaposition and between the objective 3 and sensitized surface 2, as diagrammatically illustrated in Figs. 30, 31 and 32. As indicated in these figures, the diffo 32k is composed of segmental afocal plates 28k, 29k, 30k and 31k, having apices meeting at a common center which is preferably in the optical axis of the objective 3. The plates 28k are of a suitable thickness for displacing the convergence point plane of rays emanating from the region 5 into coincidence with the surface 2; the plates 29k are of suitable thickness for displacing the convergence point plane of rays emanating from the region 6 into coincidence with the surface 2; the plates 30k are of suitable thickness for displacing the convergence point

plane of rays emanating from the region 7 into coincidence with the surface 2, and the plates 31k are of suitable thickness for displacing the convergence point plane of rays emanating from the region 8 into coincidence with the surface 2. An analyzer disk 141 is mounted in close juxtaposition axially to the diffo disk 32k and is composed of alternating segments of polarity-analyzing material, such as polaroid. The segments 141a are suitable for passing only rays having the polarity of the region 5 and register with the segments 28k. The segments 141b are suitable for passing only rays having the polarity of the region 6 and register with the segments 29k. The segments 141c are suitable for passing only rays having the polarity of the region 7 and register with the segments 30k. The segments 141d are suitable for passing only rays having the polarity of the region 8 and register with the segments 31k.

When such stationary analyzer and diffo are used in conjunction with and in close juxtaposition to the objective 3, the polarized light from the region 5 will pass primarily through the segments 141a and the convergence points of such rays will be shifted by the complementary thin plate 28k of the diffo to a plane coincident with that of the sensitized surface. Similarly, the rays emanating from the region 6 will pass primarily through the analyzer segments 141b and the convergence points of such rays will be further displaced by the next thicker afocal plate 29k of the diffo so as to bring such points into coincidence with the plane of the sensitized surface. Similarly, the rays emanating from the region 7 will pass primarily through the sectors 141c and the convergence points of such rays will be displaced still further by the next thicker afocal plate 30k of the diffo so as to bring such points into coincidence with the plane of the sensitized surface. And the polarized rays emanating from the region 8 will pass primarily through the analyzer sectors 141d and the convergence points of such rays will be still further displaced by the thickest afocal plate 31k of the diffo until they are in substantial coincidence with the sensitized surface.

Should the use of such segments reduce the size of the illuminated portion of the field on the lens or on the film, a more symmetrical and more nearly uniform distribution of the light may be secured by the arrangements shown in Figs. 33 and 34. In this arrangement the analyzer 142 is composed of a series of strips 142a, 142b, 142c, 142d having parallel edges, and the afocal plates 28m, 29m, 30m and 31m of the diffo 32m are composed of complementary transparent strips. The respective strips are of such thicknesses that they displace the convergence-point planes of each group of rays the distances necessary to bring all the points into coincidence with the sensitized surface.

The planes of vibration of the rays which will be passed by the sectors or strips are indicated by the directions of the arrows thereon.

Differential regional illumination by rays having different rates of vibration

To carry out our method of photography by photographically illuminating the different regions of an object space by rays having different rates of vibration, (that is, different colors whether visible or invisible) we may use apparatus such as illustrated diagrammatically in Figs. 35 to 38.

For such purposes the respective regions 5, 6, 7 75

and 8 may be continuously illuminated by suitable sources of light such as the lamps 10a, 11a, 12a and 13a which are similar to the lamp assembly containing the lamp 10a with their housing stationary and so positioned angularly that the light from each lamp is thrown upon the region to which it appertains only. In addition to or in lieu of the condensing lenses, the shields 117 support light filters 10n, 11n, 12n and 13n, such as violet, green, yellow and red glasses, by which the rate of vibration of the light reaching the respective regions is varied.

When such a system of illumination is used in conjunction with a diffo, such as the diffo 32n having the afocal plates 28n, 29n, 30n and 31n of progressively increasing thicknesses, there is mounted on the shaft 1b, in front of the objective 3, a disk 150 containing a set of color filters 150a, 150b, 150c and 150d complementary to the respective afocal plates 28n, 29n, 30n and 31n. The filter 150a permits the passage of substantially no light other than that having the rate of vibration of the violet light illuminating the region 5, and when the filter 150a is in registration with the objective 3 the convergence points of the rays passing through the objective are displaced by the afocal plate 28n into coincidence with the sensitive surface 2. The filter 150b passes only light having the rate of vibration of the green light illuminating the region 6, and when this filter is in registration with the objective 3, the convergence points of the rays passing through the objective are displaced by the afocal plate 29n a distance sufficient to bring the plane of such points into coincidence with the sensitized surface 2. The filter 150c passes only light having the rate of vibration of the yellow light illuminating the region 7, and, when such filter is in registration with the objective 3, the convergence points of the rays passing therethrough are shifted by the afocal plate 30n a distance sufficient to bring them into coincidence with the sensitized surface 2. The filter 150d permits the passage of substantially no light other than that having the rate of vibration of the red light illuminating the region 8, and when this filter is in registration with the objective 3 the convergence points of the rays passing therethrough are displaced by the afocal plate 31n a distance sufficient to bring the convergence points into registration with the sensitized surface 2.

In lieu of the movable diffo and color filters, there may be used stationary diffos and color filters of construction and placement similar to the showing of Figs. 30 to 34, except for the substitution of color filters for polarity analyzers.

Systems characterized by chromatizers

It is well known that light rays having a high frequency of vibration, or rays from the violet end of the visual spectrum, are optically converged by a lens at a sharper angle than light rays having a lower frequency of vibration, viz., rays from the red end of the visual spectrum emanating from the same source. Image rays from a more distant point are optically converged by a lens at a sharper angle than image rays from a less distant point. By proper co-ordination of these phenomena and appropriate lighting of the various regions of an object space we are enabled, in accordance with our invention, to bring into coincidence the convergence-point-planes of the several regions.

By lighting the regions of the object space by

groups of rays each having a different rate of vibration or color as indicated in Fig. 35 and coordinating therewith a suitable chromatizer back of the objective, the sharpness of the angles of convergence of image rays from a more distant object may be wholly or partly offset if such image rays are of red light by the lesser angle of convergence of such light, and the smaller angle of convergence of image rays from a close object may be wholly or partly offset or neutralized if such image rays are of violet light by the sharper angle of convergence of such light having a high frequency of vibration.

The principles involved in this embodiment of our invention are illustrated diagrammatically in Figs. 39 to 43 of the drawings considered in conjunction with an object space illuminated as shown in Fig. 35.

Fig. 39 illustrates diagrammatically and to a greatly exaggerated degree the effect of the passage of parallel rays of light to and through a lens 3a, which is not corrected for chromatic aberration. In the bundle of light travelling in the direction of the arrow, the red rays travelling parallel to the optical axis are indicated by the lines 160, which by their passage through the lens 3a are converged to the point 160a. The rays of violet light travelling parallel to the optical axis are indicated by the lines 161 and by their passage through the lens 3a they are converged to the point 161a. The remaining visual rays travelling parallel to the optical axis will be converged by their passage through the lens 3a to points along the optical axis between the points 160a and 161a.

Fig. 40 illustrates diagrammatically and to a greatly exaggerated degree the effect of the passage through a chromatically corrected lens 3b of image rays emanating from points at different distances from the lens along the optical axis. As shown in this figure, a bundle of image rays emanating from the close-by object point 170 diverges as indicated by the lines 170' toward the collective face of the lens 3b, and by their passage through such lens are converged to the remote point 170a. Rays emanating from a more distant object point 171 diverge as indicated by the lines 171' toward the collective face of the lens 3b and by their passage through such lens are converged to the image point 171a which is closer to the lens than the image point 170a. Similarly rays emanating from other object points and passing through the lens will be converged to image points at different distances from the lens.

In Fig. 41 there is indicated diagrammatically and to an exaggerated degree how the phenomena illustrated by Figs. 39 and 40 may be coordinated. As indicated in this figure, the point 170x is illuminated solely or primarily by violet light, which diverges from such point as indicated by the lines 170x' toward the collective face of a lens C, which has chromatic aberration. The passage through the lens 3c of violet light emanating from a close-by source 170x results in the convergence of these rays to a point 170x''. If simultaneously the point 171x be illuminated solely or primarily by red rays, the rays emanating therefrom will diverge as indicated by the lines 171x' toward the collective face of the lens 3c. Since the rays emanating from the point 171x are red rays they are bent by their passage through the lens at a lesser angle than would be bent violet rays emanating from the point 171x, and the red rays actually emanating from such point are converged to a point 171x'' substantially coincident with the point 170x''. Thus by properly choosing and suitable inter-relating the wave lengths of the colored lights, the focal length of the lens, the amount of chromatic aberration of the lens, and the distances of the points of origin of the variously colored light rays, there may be brought to a common plane the convergence points of rays emanating from different regions. By thus bringing light coming from objects at different distances from an objective to the same back focus, black and white photography on a pan-chromatic sensitized surface in such convergence-point-plane may be effected.

For practical purposes it is deemed advantageous in the utilization of this optical system for increasing the working range to use for photography, as shown in Fig. 42, a standardized corrected lens 3 in the camera 1 and to place in front of or behind such objective a supplemental optical element or system which will introduce the desired amount of chromatic aberration into the assembly and for brevity we shall designate such chromatic-aberration-producing elements "chromatizers."

As illustrated in Fig. 43, a chromatizer may be formed by the combination of a convex or positive lens 180 and a concave or negative lens 181 made of different sorts of glass having different indices of refraction. The lens dimensions are so selected that little or no focal action is produced by the assembly, but considerable controllable dispersion is produced, the action being somewhat similar to that of the so-called "direct vision prism" for spectroscopic work.

The red rays of the beam of light indicated by the lines 160', after passing through the chromatizer, travel along parallel or nearly parallel lines 160''. The violet rays of the beam, indicated by the dash lines 161', after passing through the chromatizer travel along parallel or nearly parallel lines 161'', which are considerably separated from the lines indicating the red rays. It will thus be seen that the action of the chromatizer is essentially to separate light rays of different color by chromatic aberration without introducing any substantial amount of focusing action, and the focusing of the rays to form image points is effected by means of the lens 3 which converges the rays to convergence points in substantially the same plane.

The chromatizers may be designed to suit different conditions and those having the largest amounts of chromatic aberration will be suitable for the production of an increased working range in a system where very near and extremely far objects must both be kept in acceptable focus. Chromatizers having less chromatic aberration will provide a lesser working range and would, therefore, be more suitable for use in front of the objective on relatively shallow sets where the nearest and more distant objects to be photographed in acceptable focus are not widely separated.

To secure the best photographic results, the color of all stationary objects on the set should be either grey or a color complementary to the color of the corresponding regional illumination. Mobile objects which pass from region to region should preferably be as nearly grey as possible.

Where local and variable lighting is required, as, for instance, the concentration of a beam from a more or less broadly focused spot light,

the color of the spot or concentrated light should be changed so that it shall at all times be the color of the light of the region in which the person or object to be "spotted" is located. If a person is in the region where the illumination is green in color, the spot light thrown on such person should also be green, and the movement of such person into a region where the illumination is red should result in the change of the spot light to red to keep such person in equally sharp focus. Such change in the color of the spot light may be produced by the motion of the spot light or the focusing thereof for different distances of throw, such motion or focusing ordinarily changing the color of the filter through which the light from the spot light passes.

By illuminating certain regions of the object space in accordance with the chromatic characteristics of the chromatiser and illuminating other regions of the object space with light of a color compatible with the action of the chromatiser, a variety of effects may be produced. For instance, it is possible to have the foreground and background of the set in sharp focus and to have the intervening regions relatively soft in focus by changing, to a desired extent, the color of the light falling on the intervening region.

In the operation of systems including a chromatiser it is noted that—

1. The nearer the spectral bands of color which are each used to illuminate a given plane or region of the object are spaced, the better will be the action of the entire system.

2. The more numerous the colored bands which are selected and the closer the planes or regions illuminated by them, the better will be the operation of the system.

3. The less the "spill-over" of lights of the various colors from one region into another, the better the operation of the system.

4. The distances of the various color-illuminated planes or regions from the objective lens will depend upon the selection of the colors used. In general, the greater the differences in wavelength between colors illuminating adjacent planes, the greater the corresponding separation of such planes.

5. The chromatisers may be either entirely afocal or may have a small focal action if desired. They constitute what is known as a "hyperchromatic system."

6. There may be provided for each standard objective of a given focal length, a set of chromatisers each of which may be marked with the distances of the nearest and farthest objects within the working range of the system when properly set up.

7. Alternatively, sets of lenses of a given focal length but having different chromatic aberrations (and therefore different working ranges) could be provided.

8. The method is only applicable to standard photography in black-and-white and is not available in its present form for color photography.

9. To a limited extent the system may be used outdoors under certain conditions provided that reversed chromatic aberration is designedly placed in the system. That is, if the system is arranged so that violet light is brought to a focus further from the objective than red light (by suitable change of the lens components, or design of the chromatisers), a limited action outdoors is obtainable, as follows: The more distant

objects are the blue sky and the violet haze covering distant hills. The objects in the middle ground are generally green trees, green grass, and the like. The foreground actors or objects (preferably with a maximum amount of red in clothing or the objects themselves) may be placed relatively in the shade (so far as natural illumination is concerned) and may then be brightly illuminated artificially by red light (from a "booster" installation).

There may be thus produced a sequence of colored objects at different distances crudely corresponding to the requirements for increased working range; and it is therefore possible to get an increased working range even for outdoor subjects of suitable types, photographed for black-and-white pictures, by the method described. If no foreground colored illumination or coloration of foreground objects is used, it is even possible to take natural color photographs by this method.

Use of multiple layer film

Instead of bringing to a common plane the convergence points of image rays from different regions, as above described, we may augment the differences between the planes of the convergence points of rays emanating from different regions by illuminating such regions by colored lights in the reverse order from that above described in connection with Figs. 35, 39-43. That is to say, as diagrammatically indicated in Fig. 44, the objects in the foreground 5 may be illuminated by red rays, the objects in the middle foreground 6 may be illuminated by yellow rays, the objects in the middle background 7 may be illuminated by green rays, and the objects in the background 8 may be illuminated by violet rays.

When the object space is so illuminated the closeness of the region 5 and the slowness of the rate of vibration of the red rays cause to make more gradual the convergence angle indicated by the lines 185, 186 of rays indicated by lines 185, 188 emanating from the region 5 and converged by the objective 3. Conversely, the distance of the region 8 and the rapidity of vibration of the violet rays cause to make sharper the convergence angles indicated by lines 182, 189 of rays indicated by the lines 182, 186 emanating from the region 8 and converged by the objective 3. The rays emanating from the regions as indicated by the lines 184, 188 and 183, 187 will be similarly affected as indicated by the lines 184, 187 and 183, 188.

This increase in the distance between the convergence point planes of the rays from the different regions makes it possible to use films composed of superimposed layers having surfaces sensitized respectively to particular colors of the spectrum. For simplicity there is preferably used a multiple layer film having surfaces coated with emulsion sensitive to three different colors. For instance, the front surface 200 may be coated with an emulsion sensitive to violet-blue rays; an intermediate surface 201 may be coated with an emulsion which is sensitive to green-yellow rays; and the rear surface 202 may be coated with an emulsion which is sensitive to red rays. Such films are now available on the market under such names as "Kodachrome" or "Gaspar-color".

By the spacing of the convergence point planes proportionately to the spacing of the color selective sensitized surfaces, the objects in the foreground will be sharply photographed on the sensitized surface 202, the objects in the middle

ground will be sharply photographed on the intermediate sensitized surface, and objects in the background will be sharply photographed on the sensitized surface 200.

A photograph so obtained will be a color reproduction of the color spaces and will generally not be suitable for exhibition purposes, but black-and-white negative or positive prints made therefrom will meet the requirements of black-and-white projection and exhibition and will show sharp images of objects throughout the set.

Rear projection

In photographing a scene on a set, it is frequently desirable to supply or augment the background by the stereopticon or kinematographic reproduction of objects or scenes on a translucent screen at the rear of the set. The projection is preferably done from the rear of the screen. When a set is being photographed in accordance with our increased range system, such rear projection on the screen at the back of the set, as indicated in Fig. 1, may be made to conform with the conditions prevailing in the region 8. For instance, when the set is being photographed by the use of our method employing periodical illumination, the rear projector may be so equipped as to project on the rear screen only when the rear region is illuminated; when the identification of rays from the rear region is due to a particular polarization of light in such rear region; the light forming the translucent screen-image may be similarly polarized; and when the identification of light emanating from the rear region is colored, the light projected on the translucent rear screen may be similarly colored.

Having described our invention, we claim:

1. In the art of image formation by means of an optical objective, the steps which include creating image-forming ray bundles appurtenant to and identifiable with an object-distance axially from an objective, dioptrically forming such ray bundles and no others into an image section, changing the back focal distance of such image section by shifting the rays of such bundles parallel to the optical axis of the objective converging such rays and thereby effecting the axial displacement of the plane or convergence points of a group of image-forming rays appurtenant to and identifiable with such object distance from the objective, such displacement being along said optical axis and the convergence points of such group retaining substantially the same radial relationship to one another and to the optical axis which such points would have had if undisplaced, creating image-forming ray-bundles appurtenant to and identifiable with a second object distance from the objective, dioptrically forming said second named ray-bundles and no others into an image section complementary to the first image section by converging such bundles to image points without an axial shift of the rays of the last named bundles equal to the shift first specified, such displacement varying the axial spacing between the first named plane and the plane of convergence points of the second named group of image-forming rays originating at a distance from the objective different from the first-named group, and receiving the image points of both such groups upon a surface, the image points of both such groups forming constituents of a composite image substantially devoid of overlay of image points of given object points by circles of confusion from the same object points.

2. In the art of image formation on a medium by means of an optical objective having an optical center, the steps which include illuminating a plurality of objects in the object space of the objective by light having predetermined characteristics identifiable with the distances of the objects respectively from the optical center and imparting identifiable characteristics to image rays passing from such objects toward image planes, segregating image-forming rays emanating from one of such objects from the other rays and converging them toward convergence points in a plane, segregating image-forming rays emanating from another of such objects from the first named rays and converging them toward convergence points in a plane axially spaced from said first named plane, and shifting unequally to one another the planes of convergence points of rays from objects at different distances from the optical center so that such convergence points lie in substantially the same plane coincident with the plane of the medium and form a composite sharp image thereon substantially devoid of overlay of image points from given object points by circles of confusion from the same object points.

3. In the art of image formation on a medium by means of an optical objective having an optical center, the steps which include illuminating a plurality of objects spaced unequally from the objective in the object space thereof, the illumination of the respective objects including groups of rays each having predetermined characteristics identifiable with the distances of the objects respectively from the optical center and imparting identifiable characteristics to image rays passing from the respective objects toward image planes, dioptrically forming image rays identifiable with one of said distances exclusively into an image section and changing the back focal distance thereof by axially displacing converging rays of one of such identifiable groups axially of the system to shift the convergence-point plane of such group to a plane substantially coincident with the convergence-point plane of another group of rays emanating from another of said objects and which have not been correspondingly shifted, and receiving said points on a medium to form an image substantially devoid of overlay of image points from given object points by circles of confusion from the same object points.

4. In the art of image formation on a medium by means of an optical objective having an optical center, the steps which include illuminating a plurality of objects spaced unequally from the objective in the object space thereof by segregable groups of rays each having characteristics identifiable with the distances of the objects respectively from the optical center and imparting pre-determined characteristics respectively to image rays emanating from the respective objects, dioptrically forming image rays identifiable with one distance exclusively into one image section and dioptrically forming image rays identifiable with a different distance exclusively into another image section complementary to the first section, shifting relatively to one another the rear focal distances of the images formed of the respective objects by axially displacing converging rays of one of such identifiable groups axially from the optical center to shift the convergence points of such group to a plane substantially coincident with the plane of convergence to points of another group of rays

emanating from another of said objects, selectively eclipsing the passage of rays from each of said objects toward the medium during convergence of rays from the other of the said objects, and receiving said converged rays from different objects on said medium selectively.

5. In the art of image formation by means of an optical objective having an optical center, the steps which include providing occulting illumination of objects in the object space of said objective and eclipsing one of said objects at a predetermined distance axially from said center when another of said objects at a different predetermined distance axially from said center is illuminated to create image forming rays emanating therefrom and identifiable with the distance thereof from the objective and vice versa, dioptically forming an image exclusively from the image rays identifiable with one object distance and dioptically forming an image exclusively from image rays identifiable with another object distance by converging the image rays emanating from the respective objects and changing the back focal distance of one image by axially shifting converging rays from one object when illuminated to form convergence points in a plane substantially coincident with the plane in which rays from the other object when illuminated will converge to image points.

6. In the art of image formation by means of an optical object having an optical center, the steps which include intermittently illuminating each of a plurality of objects in the object space of the objective by rays respectively identifiable with the respective differences of the respective objects from said center, segregating image rays emanating from the respective objects and separately converging the rays identifiable with each distance respectively and axially shifting converging rays emanating from at least one of said objects to converge such rays to points in a plane displaced axially from the natural plane of convergence to points of such converging rays and thereby changing the natural interval between the image planes resulting from the axial interval between such objects, and maintaining after the displacement of said rays substantially the same radial relationship thereof to one another and to the optical axis which such points would have had if not axially displaced.

7. In the art of image formation by an optical objective having an optical center, the steps which include illuminating objects in the object space of the objective and respectively at different distances axially from said center by rays including groups of rays each having vibratory characteristics differing from the other and each identifiable with the respective axial distances of one of the respective objects, segregating the respective groups of rays and dioptically converging the rays identifiable with one distance separately from rays identifiable with another distance and vice versa while varying unequally the rear focal distances of the planes of images formed by the respective groups by displacing axially converging rays having one vibration characteristic to convergence points in a plane coincident with the convergence points of rays having different vibration characteristics.

8. In the art of image formation by an optical objective having an optical center, the steps which include illuminating objects in the object space of the objective and respectively at different distances axially from said center by groups of rays each having vibratory charac-

teristics different from one another and identifiable respectively with the axial distance of one of the respective objects, segregating the rays of respective groups and dioptically converging the rays identifiable with one distance separately from rays identifiable with another distance and vice versa while varying unequally the rear focal distances of the images formed by the respective groups by displacing axially converging rays having one vibration characteristic to convergence points in a plane coincident with the convergence points of rays having different vibration characteristics, and eclipsing rays having one vibration characteristic and passing through the optical center at one angle during convergence of rays having another vibration characteristic and passing through the optical center at a different angle due to the axial interval between the objects.

9. In the art of image formation by means of an optical objective having an optical center, the steps which include illuminating objects in the object space of the objective and respectively at different distances axially from said center by rays including groups of rays having different rates of vibration, each such group being identifiable with the respective distances of the respective objects, and converging to image points the respective groups of rays while changing the rear focal distance of the plane of the image formed by one group relative to the rear focal distance of the plane of the image formed by the other group by shifting axially converging rays having one rate of vibration to form convergence points in a plane substantially coincident with the plane of convergence to points of rays having a different rate of vibration.

10. In the art of image formation by means of an optical objective having an optical center, the steps which include illuminating objects in the object space of the objective and respectively at different distances axially from said center by groups of rays having different rates of vibration to form image ray groups emanating from such objects and each, identifiable with the distance of one of said objects dioptically converging the respective groups toward rear focal planes having an axial interval between them, shifting axially converging rays having one rate of vibration to shift their convergence points into a plane substantially coincident with the plane of convergence to points of rays having a different rate of vibration, and eclipsing rays having one rate of vibration during the convergence of rays having a different rate of vibration.

11. In the art of image formation by means of an optical objective having an optical center, the steps which include illuminating objects in the object space of the objective and respectively at different axial distances from said center by rays including groups of rays each having a different plane of vibration, each such group being identifiable with the axial distance of one of said objects, segregating rays from the respective objects and dioptically converging the rays from the respective objects toward axially spaced image planes and shifting axially converging rays having one plane of vibration to form convergence points in a plane substantially coincident with the plane of convergence to points of rays having a different plane of vibration.

12. In the art of image formation by means

of an optical objective having an optical center, the steps which include illuminating objects in the object space of the objective and respectively at different distances axially from said center including groups of rays each having a different plane of vibration, each such group being identifiable with the distance of one of said objects, dioptrically converging the respective groups of rays toward image planes axially spaced from one another, shifting axially converging rays having one plane of vibration to form convergence points in a plane substantially coincident with the plane of convergence to points of rays having a different plane of vibration, and eclipsing rays having one plane of vibration during the convergence of rays having a different plane of vibration.

13. In the art of image formation by means of an optical objective having an optical center, the steps which include illuminating a plurality of objects in the object space of the objective and respectively at different distances axially from said center by rays including groups of rays each having an identifiable characteristic, each of said groups of rays being identifiable with a particular object, dioptrically and concurrently converging rays emanating from said objects toward convergence points, and axially shifting converging rays identifiable by one characteristic with an object at one distance to form convergence points in a plane substantially coincident with convergence points of rays identifiable by another characteristic of an object at a different distance, the radial relationship of the convergence points of the shifted rays being substantially unaffected by the axial shift thereof.

14. In a system for the formation of images, the combination with an image-receiving medium and an optical objective cooperatively related thereto and having an optical center, of means for illuminating objects in the object space of the objective and at different axial distances from said center, such illumination including segregatable groups of rays identifiable with the respective axial distances of the respective objects illuminated thereby, said objective converging a group of rays from one of said objects toward convergence points in a plane and converging a group of rays from another of said objects toward points in a second plane spaced from the first named plane, and means for shifting, the convergence-point plane of rays of one of said groups and no others identifiable with one object distance relative to the convergence plane of rays of another of said groups identifiable with a different object distance to diminish the axial interval between such planes.

15. In a system for the formation of images, the combination with an image-receiving medium and an optical objective having an optical center, of means for illuminating objects in the object space of the objective at different axial distances from said center, such illumination including groups of rays identifiable with the respective axial distances of the respective objects illuminated thereby, said objective converging a group of rays from one of said objects toward convergence points in a plane and converging a group of rays from another of said objects toward points in a second plane spaced from the first named plane, means for shifting the convergence point plane of rays of one of said groups relatively to the convergence point plane

of rays of another of said groups to diminish the axial interval between such planes, and means for eclipsing the rays of one of said groups during passage to the medium of rays from the other of said groups.

16. In a system for the formation of images, the combination with an optical objective having an optical center and a medium for receiving an image therefrom, of means for occultingly illuminating and eclipsing objects in the object space of the objective and at different axial distances from said center, the illumination of each object having predetermined characteristics identifying it with the distance of the object which it illuminates, and means for shifting axially converging rays emanating from one of said objects and identifiable with its distance only without materially altering the radial relationships of convergence points formed thereby toward the plane of convergence points formed by rays emanating from another of said objects during the eclipse of image rays from said last named object.

17. In a system for forming images, the combination with an objective having an optical center and a medium for receiving an image from the objective, of means for intermittently illuminating and eclipsing objects in the object space of the objective and respectively at different distances from said center, such means including structure rendering groups of rays identifiable with the respective axial distances of said objects respectively, the illumination of one of said objects being eclipsed during the illumination of another thereof, said objective converging image rays from the respective objects toward image planes having an axial interval between them proportioned to the axial interval between said objects, and means for axially shifting image rays identifiable with one object distance exclusively during the convergence of such rays by the objective so as to form convergence points from said rays in a plane substantially coincident with the plane of convergence of points of rays emanating from another of said objects and during the eclipse of image rays from said last named object.

18. In a system for forming images, the combination with an objective having an optical center and an image-receiving medium cooperative therewith, of means for illuminating and eclipsing objects in the object space of the objective and at unequal axial distances from said center by rays, including groups of rays each having a different vibration characteristic and each identifiable with the distance of one of said objects, said objective converging image rays from the respective objects toward image planes having an axial interval proportional to the axial interval between said objects, and means for axially shifting, independently of other rays, rays having one vibration characteristic to form convergence points in a plane substantially coincident with the plane of convergence of points of rays having different vibration characteristics during the eclipse of said last named rays.

19. In a system for forming images, the combination with an objective having an optical center and an image-receiving medium cooperative therewith, of means for illuminating objects in the object space of the objective and at different axial distances from said center by rays including groups of rays each having a different vibration characteristic and each identifiable with the distance of one of said objects, said objective

converging image rays from the respective objects toward image planes axially spaced by reason of the axial interval between said objects, means for axially shifting rays having one vibration characteristic identifiable with one of said objects and exclusively of rays from objects at different distances to form convergence points in a plane substantially coincident with the plane of convergence of points of rays having different vibration characteristics and identifiable with the other of said objects, and means for eclipsing the passage to the medium of rays having one vibration characteristic during the passage thereto of rays having another vibration characteristic.

20. In a system for forming images, the combination with an objective having an optical center and an image receiving medium cooperative therewith, of means for illuminating and eclipsing objects in the object space of the objective and at different axial distances from said center by rays, including groups of rays having different rates of vibration, each of said groups being identifiable with the distance of one of said objects, said objective converging image rays from said objects toward image planes spaced axially from one another, means for segregating the identifiable rays from the respective objects, and means for axially shifting converging rays of a group having one rate of vibration exclusively of the rays from objects at different distances so as to form convergence points of such shifted rays in a plane substantially coincident with the plane of convergence to points of rays of a group having a different rate of vibration during the eclipse of said last named group.

21. In a system for forming images, the combination with an objective having an optical center and an image receiving medium cooperative therewith, of means for illuminating and eclipsing objects in the object space of the objective at different axial distances from said center by rays, including groups of rays having different rates of vibration, each of said groups being identifiable with the distance of one of said objects, said objective converging the respective groups of rays toward planes axially spaced from one another, means for shifting the back focal distance of an image formed by converging rays of a group having one rate of vibration, and exclusively of rays from objects at different distances, relatively to the plane of an image formed by the convergence to points of rays of a group having a different rate of vibration, said means eclipsing the passage to the medium of a group of rays from an object at one distance from said center during the passage thereto of a group of rays from an object at a different distance from said center.

22. In a system for forming images, the combination with an objective having an optical center and an image receiving medium cooperative therewith, of means for illuminating and eclipsing objects in the object space of the objective and at different axial distances from said center by rays, including groups of rays having different rates of vibration, each of said groups being identifiable with the distance of one of said objects, and means registering with said objective on the illumination of an object remote from said center for axially shifting converging rays identifiable with the distance of the remote object only so as to form convergence points of such rays in a plane substantially coincident with

the plane of convergence-to-points of rays emanating from an object nearer said center during the eclipse of said last named rays.

23. In a system for forming images, the combination with an objective and an image receiving medium cooperative therewith, of means for illuminating and eclipsing objects in the object space of the objective and at different distances therefrom by rays, including groups of rays having different rates of vibration, each of said groups being identifiable with the distance of one of said objects, said objective converging image rays from the respective objects toward image planes axially spaced from one another, 10 means for changing the rear focal distance of an image formed by converging rays of one group only relatively to the rear focal distance of an image formed by the convergence to points of rays of another group, and means for eclipsing 15 passage to the medium of rays of each group during passage thereto of rays of the other group.

24. In a system for forming images, the combination with an objective having an optical center and an image-receiving medium cooperative therewith, of means for illuminating and eclipsing objects in the object space of the objective at different distances from said center by rays, including groups of rays having different 25 planes of vibration, each of said groups being identifiable with the distance of one of said objects, said objective converging rays from said objects toward planes conjugate to the respective objects and axially spaced from one another, and means for changing the rear focal distance of an image formed by converging rays of one group relatively to the plane of an image formed by convergence to points of rays of another group during the eclipse of the latter.

25. In a system for forming images, the combination with an objective and an image-receiving medium for receiving images therefrom, of means for illuminating objects in the object space of the objective at different axial distances therefrom by groups of rays having different planes of vibration, said means including structure effecting identification of each of the respective groups with the distance of one of said objects, said objective converging the rays of the respective 45 groups toward axially spaced image planes, means including transparent members of unequal thickness and including further structure coordinating the members and illumination so that the thicker member registers with the objective during the illumination of an object remote from the objective for axially shifting converging rays from such remote object to form convergence points of such rays in a plane substantially coincident with the plane of convergence to points of rays from an object nearer said objective, and said second named structure eclipsing passage through the members to the medium of rays of each group during passage therethrough of rays of the other group.

26. In the art of photography through an objective, the steps which include illuminating objects unequally spaced from the objective by light including groups of rays each having a distinguishing characteristic appurtenant to and identifiable with the distances of the respective objects, converging light rays passing from one object through the objective to convergence points in a plane, and converging light rays from a differently spaced object through the objective,

segregating the groups of rays relatively to one another, and displacing the plane of the convergence points of the second rays independently of the first rays and to substantially the plane of the convergence points of the first rays.

27. A method of image formation by subjecting a photosensitive surface to image rays passing through an objective from an object space of greater depth than the working range of the objective which consists in segregating from one another rays emanating at different distances from the objective and converging image rays from one region of lesser depth than the object space to convergence points in a plane in substantial coincidence with the sensitive surface, and then converging image rays from a second region of lesser depth than the object space to convergence points while shifting them independently of rays from the first region to a plane substantially coincident with the plane of the sensitive surface, the light rays from one region being excluded from the sensitive surface when rays from the other region are admitted thereto.

28. In a method of image formation by subjecting a sensitive surface to rays passing through an objective from an object space of greater depth than the normal working range of the objective which includes segregating from one another rays emanating at different distances from the objective and shifting converging rays from different regions of the object space parallel to themselves so as to shift the planes of the convergence points of such rays independently of one another and differentially axially along the optical axis without substantially changing the radial relationship of such convergence points to the optical axis and thereby unequally varying the rear focal distance of the images formed by the image rays from the regions at different distances from the objective.

29. A method of photography which includes subjecting a plurality of photo-sensitized surfaces spaced one behind the other and each surface being photo-sensitive to light rays of a character to which the other surface is substantially photo-insensitive, to the action of light rays passing through an optical system including a chromatizer and an objective both of which are in front of both sensitized surfaces, said light rays resulting from illuminating axially spaced regions of the object space of the optical system by groups of light rays, confining the illuminating of objects in each region to rays of one group only each group being of a character to which one of said surfaces is photo-sensitive and the other of said surface is substantially photo-insensitive, the first sensitized surface behind the optical system being photo-sensitive to light rays of the character illuminating only the region most remote from the optical system and the sensitized surface most remote from the optical system being sensitive to light rays of the character illuminating only the region nearest the optical system, said chromatizer and objective coacting to bend rays emanating from said remote region to convergence points in the plane of said first sensitized surface, and coacting to bend the converged light rays from the nearest region to convergence points in the plane of the most remote sensitized surface.

30. In the art of image formation by means of an optical objective, the steps which include illuminating regions at different axial distances from the objective with identifiable and segregatable groups of rays, confining the illumina-

tion of objects in each region to a group of rays with which it is identifiable, segregating and converging the respective ray groups to axially spaced image planes independently of one another, displacing the plane of convergence points of a group of image-forming rays appurtenant to and identifiable with a region at a remote distance from the objective, such displacement being along the optical axis and the convergence points of such group retaining substantially the same radial relationship to one another and to the optical axis which such points would have had if undisplaced, and such displacement decreasing the axial spacing between such plane and the plane of convergence points of a group of image-forming rays originating in a region nearer the objective.

31. In the art of image formation on a medium by means of an optical objective, the steps which include illuminating and eclipsing a plurality of objects in the object space of the objective and at different axial distances therefrom by rays respectively having characteristics identifiable with the respective distances of the respective objects, converging image-forming rays emanating from each of such objects toward convergence points in planes having an interval between them complementary to the axial interval between said objects, and shifting relatively to one another said medium and the plane of convergence points of rays from one of said objects during the eclipse of rays from the other of said objects.

32. In the art of image formation on a medium by means of an optical objective, the steps which include illuminating a plurality of objects spaced unequally from the objective in the object space thereof, confining the illumination of the respective objects to segregatable groups of rays each having characteristics identifiable with the distances of the objects respectively, dioptrically converging image rays from said objects toward image planes having an interval between them due to the spacing of said objects, axially displacing converging rays of one of such identifiable groups axially to shift the convergence-point plane of such group relatively to the convergence point plane of the other of such groups.

33. In the art of image formation on a medium by means of an optical objective, the steps which include illuminating and eclipsing a plurality of objects spaced unequally from the objective in the object space thereof, the illumination of the respective objects including groups of rays each having characteristics identifiable with the distances of the objects respectively, dioptrically converging image rays from the respective objects toward image planes having an axial interval between them due to the spacing of said objects, axially displacing converging rays of one of such identifiable groups axially of the system, the passage of rays from one of said objects to the medium being eclipsed during convergence of rays from the other of the said objects.

34. In the art of image formation by means of an optical objective, the steps which include occultingly illuminating and eclipsing objects at different distances from the objective in the object space of said objective so that when one of said objects is illuminated another object is eclipsed, dioptrically converging image rays from the respective objects toward image planes having an axial interval between them due to the

spacing of the objects, and axially shifting converging rays from one object when illuminated to form convergence points in a plane axially displaced from the plane in which rays from such object when illuminated would be converged to image points by the objective alone.

35. In the art of dioptric image formation from a scene having a plurality of objects in regions at different distances axially from an optical center, the steps which include illuminating selected regions of the scene by segregatable light rays of predetermined characteristics identifiable with the axial distances of the respective regions, collecting image rays from the objects in the respective regions, and dioptrically converging them toward rear focal planes spaced from the optical center and having an axial interval between them, selectively segregating the beams from the respective regions, and selectively increasing the rear focal distance of the plane of an image formed by segregated rays from one region independently of and relatively to the rear focal distance of an image formed by segregated rays from another region to provide a composite controllably sharp scene image of the objects in both regions.

36. In the art of dioptric image formation from a scene having a plurality of objects in regions at different distances along an optical axis from an optical center, the steps which include illuminating the respective regions to form segregatable image rays identifiable selectively with the distances of objects in the respective regions by their characteristics included in the group, viz., time of occurrence, rate of vibration and plane of vibration, collecting and segregating image rays from objects in the respective regions during their passage toward image planes, dioptrically forming an image by converging said rays toward rear focal planes having an axial interval between them proportionate to the axial interval between the objects in the respective regions, and increasing the rear focal distance of the image formed by the segregated rays from one of said regions independently of and relatively to the rear focal distance of the image formed by the segregated rays from the other of said regions to form a composite image in which the sharpnesses of the depictions of objects in both regions are unaffected by the axial interval between the objects.

37. In the art of image formation, the steps which comprise placing in cooperating relation a converging optical system and a photo-sensitive surface, establishing within the object space of the said optical system a multiplicity of spacial regions the dimensions of which parallel to the optical axis of the system in any vicinity are systematically related to the depth of field of the system in the corresponding vicinity, lighting each of the said regions with a distinctive illumination identifiable with such region only, the identifiable characteristic of the illumination

being a characteristic of the group, viz., time of occurrence, rate of ray vibration and plane of ray vibration, interposing in the path of the image forming rays reaching the above optical system a multiplicity of light selectors each of which permits by dependence on and utilization of the above-mentioned identifiable characteristic the passage of light from a single region only, said optical system including differential focus means for systematically and controllably altering the back focal length of the optical system for light emanating from each of the said regions and thus shifting the corresponding image location, and forming on the photo-sensitive surface a composite picture of the regions of the object space with each region thereof in the corresponding sharpness of focus.

38. The combination with a photo-unit having an objective and means for positioning a photo-sensitive surface in the image space of the objective, said unit including means comprising a plurality of transparent plates of different thicknesses and a complementary opaque member together providing a cycle including a photo-period and a photo-interval at the sensitive surface positioned by said first means, and means including a series of lamps and timer mechanism connected therewith for forming light flashes illuminating regions in the object space of said objective one after another during the photo-period and only one at a time, said timer mechanism and lamps cooperating to provide photo-periods of similar duration, to provide photo-intervals of similar duration and to provide photo-periods of similar intensities at rates of occurrence obviating flicker; light flashes formed by said means during the photo-period of said cycle being of photo-intensity, the regions illuminated one after another being at different distances axially from the objective, and said positioning means holding a sensitive surface stationary relative to the axis of the objective throughout a sequence of illuminations of all said regions.

39. In the art of dioptric image formation from a scene having objects in a plurality of regions at different distances from an optical objective in the direction of the optical axis of such objective, the steps which include illuminating said scene by a series of light flashes having a frequency and balance obviating visually perceptible flicker, said light flashes lighting said regions to photo-intensity one at a time, dioptrically converging toward an image plane image rays from the respective regions as they are illuminated to photo-intensity one at a time, and shifting the back focal length of image rays converged from one of said regions relatively to the back focal length of image rays converged from another of said regions.
